UNITED STATES PATENT OFFICE.

NELSON C. HALL, OF OLIN, IOWA.

TOOL.

Application filed January 9, 1922. Serial No. 528,006.

To all whom it may concern:

Be it known that I, NELSON C. HALL, a citizen of the United States, residing at Olin, in the county of Jones and State of Iowa, have invented certain new and useful Improvements in Tools, of which the following is a specification.

This invention relates to a valve testing tool and has for its object the production of a simple and efficient tool which may be applied over the valve of an engine, such as an engine used in the Ford type of automobiles.

Another object of this invention is the production of a simple and efficient mechanism for holding the air cup firmly clamped over the valve in such a position as to facilitate the testing of the valve.

With these and other objects in view the invention consists of certain novel constructions, combinations, and arrangements of parts as will be hereinafter fully described and claimed.

In the drawings:

Figure 1 is a vertical section through a portion of an engine casing showing the valve in position, the valve testing tool also being shown in connection therewith.

Figure 2 is a top plan view of the structure shown in Figure 1.

Figure 3 is a top plan view of a modified form of the invention, showing the manner in which a clamping lever may be used for the purpose of firmly holding the air cup over the valve.

By referring to the drawings it will be seen that 1 designates the engine casing, which is provided with the usual valve 2 of any suitable or desired construction. The valve 2 is adapted to normally seat upon the valve seat 3, and the purpose of the present tool is to test the closeness of the fit between the valve 2 and the seat 3 to determine whether or not air pumped into the air cup will escape between the valve and the valve seat.

An air cup 4 is used in connection with the present device and this air cup 4 is provided with a concaved channel 5 around the lower edge thereof, for the purpose of receiving a circular rubber or other gasket 6 as clearly shown in Figure 1. The air cup 4 is preferably cup shaped in form but may be carried to suit the desire of the manufacturer so far as the shape is concerned. The cup 4, however, must be made

of suitable size and shape to fit conveniently over the upper end of the valve seat and must be made larger than the valve port as is illustrated clearly in Figure 1. The cup 4 is provided with an upwardly extending reduced neck 7, this neck 7 being externally threaded at its outer end for the purpose of receiving a pump hose 8 shown in dotted lines in Figure 1.

A clamping yoke or plate 9 is fitted over the air cup 4 and this yoke 9 comprises a substantially circular central portion having an aperture 10 formed centrally thereof, through which aperture 10 extends the reduced neck 7. The yoke 9 is provided with a pair of laterally extending arms 11, these arms 11 having notched ends 12 for the purpose of fitting around the supporting bolts 13 and under the heads 14 of the bolts 13. These bolts 13 may be threaded into the engine casing as clearly shown in Figure 1 for the purpose of firmly clamping the yoke 9 down snugly over the top of the air cup 4 and causing the same to tightly fit around the valve port and constitute an air field therearound.

From the foregoing description it will be seen that air may be conveniently pumped through the holes 8 and through the reduced neck 7 which is provided with a feeding aperture 15 formed therein. The air will then pass into the cup 4 and the sealing gasket or washer 6 will prevent the escape of air from the cup. The fitting of the valve 2 upon the valve seat 3 may then be very easily and conveniently tested.

In the form shown in Figure 3 the usual cup 4^a is employed, but a flat lever 16 is used having an aperture 17 formed therein for fitting over the reduced neck 7' of the cup 4^a. One end of the lever 16 is adapted to fit under one head bolt 18, the other end 19 of the lever being free to be pressed downwardly by the operator for the purpose of firmly clamping the cup 4^a upon the head of the engine 1.

It should be understood that certain detailed changes may be made in the mechanical construction of the device without departing from the spirit of the invention so long as these changes fall within the scope of the appended claims.

1. A valve testing tool comprising an air cup, means for admitting air into a cup, said yoke comprising a plate, said cup provided with an air inlet neck, said yoke

provided with a central opening for receiving said neck, said yoke provided with laterally extending arms having notched ends, and clamping means engaging the 5 notched ends for clamping the cup over and around the valve of an engine.

2. A valve testing tool comprising an air cup, means for admitting air into said cup, a yoke fitting over the cup for clamping 10 the same in position, a sealing gasket carried by the bottom of the air cup for forming an air tight joint around the bottom of the air cup, said yoke comprising a plate, said cup provided with an air inlet neck, 15 said yoke provided with a central opening for receiving said neck, said yoke provided with laterally extending arms having

notched ends, and clamping means engaging the notched ends for clamping the cup over and around the valve of an engine. 20

3. A valve testing tool comprising an air cup, means for admitting air into said cup, a yoke comprising a plate, said cup provided with an air inlet neck, said yoke provided with an opening for receiving said neck, and clamping means engaging said yoke for clamping the cup over and around the valve of an engine. 25

In testimony whereof I affix my signature in presence of two witnesses.

NELSON C. HALL.
